UNITED STATES PATENT OFFICE.

ROMEYN B. SCRIBNER, OF RYE, NEW YORK.

DESIGN FOR A LOOP ANTENNA.

Application filed March 27, 1925. Serial No. 12,912. Term of patent 14 years.

To all whom it may concern:

Be it known that I, ROMEYN B. SCRIBNER, a citizen of the United States, residing at Rye, in the county of Westchester and State of New York, have invented a new, original, and ornamental Design for Loop Antennæ, of which the following is a specification, reference being had to the accompanying drawing, forming part thereof.

The figure is a perspective view of a loop antenna showing my new design.

I claim:

The ornamental design for a loop antenna, as shown.

ROMEYN B. SCRIBNER.
